Primary Examiner—Jeffrey Asch(74) *Attorney, Agent, or Firm*—Saidman DesignLaw Group(57) **CLAIM**

The ornamental design for portion of cork extractor, as shown and described.

DESCRIPTION

FIG. 1 is a right side and rear perspective view of a portion of cork extractor showing my new design; and, FIG. 2 is a right side perspective view thereof.

The dashed lines shown in FIGS. 1-2 represent environmental subject matter and form no part of the claimed design. The dotted lines shown in FIGS. 1-2 represent the border between claimed subject matter and unclaimed environmental subject matter and form no part of the claimed design.
